US00D888730S

(12) **United States Design Patent** (10) **Patent No.:** **US D888,730 S**
Momchilov et al. (45) **Date of Patent:** **** Jun. 30, 2020**

(54) **DISPLAY SCREEN OR PORTION THEREOF WITH GRAPHICAL USER INTERFACE**

(71) Applicant: **Citrix Systems, Inc.**, Fort Lauderdale, FL (US)

(72) Inventors: **Georgy Momchilov**, Parkland, FL (US); **Chris Pavlou**, Boca Raton, FL (US)

(73) Assignee: **Citrix Systems, Inc.**, Fort Lauderdale, FL (US)

(**) Term: **15 Years**

(21) Appl. No.: **29/678,441**

(22) Filed: **Jan. 29, 2019**

Related U.S. Application Data

(63) Continuation of application No. 16/164,258, filed on Oct. 18, 2018, which is a continuation of application No. 15/150,558, filed on May 10, 2016, now Pat. No. 10,122,709.

(57) **CLAIM**

The ornamental design for a display screen or portion thereof with graphical user interface, as shown and described.

DESCRIPTION

The sole FIGURE is a front view of a display screen or portion thereof with graphical user interface showing our new design.

The broken lines depicting the display screen and the remainder of the graphical user interface show features that form no part of the claimed design.
